UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT.

KEY-CUTTING DEVICE.

Application filed April 4, 1921. Serial No. 458,185.

My invention relates to key cutting machines and more particularly to a machine designed to cut notches or undulations in the bit of a key blank, the term "bit" being used 5 to refer to that portion of the key wherein the tumbler notches are formed. In the preferred form of my device which I have chosen to illustrate the principles of my invention, each of the notches in the key bit is 10 cut separately, and is cut to measurement, the desired depth of the notch being known in advance or predetermined. It is obvious, therefore, that while my device is highly useful in originating keys or producing a 15 new or original key bit not heretofore used, it is equally easy to duplicate any given key by cutting a bit exactly like that of the sample. It, moreover, has the great advantage over prior duplicating machines that 20 the notches cut in the key bit are cut to measurement and their depth is not controlled entirely by the depth of the notches in the sample key, the bit of which may have been so worn by use that its operation is no longer 25 satisfactory and an exact duplicate of its present shape would not be desired. As the key cutting is usually stamped upon the head of the key either directly or in code, it is possible by the use of my improved device 30 to make an exact duplicate of the key as originally cut.

While my improvements are well adapted to be used in a small machine designed to be used by a locksmith, by the manager of a 35 hotel or large building or by the manager of an automobile agency for the production and reproduction of keys to fit the locks for which they are required, they are also adapted 40 for use in machines which are to be employed in a factory where keys are to be originated and duplicated.

Heretofore, key cutting machines have sometimes been provided with a plurality of cutters, each of which cuts a notch of individual size and at a given point longitudinally of the key bit. To produce keys of different cuttings it is therefore necessary to change one or more of these cutters so that a different combination may be formed for each 45 new bit to be cut. As such a change requires the expenditure of a great deal of time and is attended by considerable trouble, such machines are unsatisfactory for cutting single keys for different locks. I, therefore, propose to use in the illustrated embodiment of 50

my invention, a single cutter and arrange for the cutting of notches of different depth and at different points along the key bit by producing relative movement, both longitudinally and transversely of the key axis, between the cutter and the key. 60

One object of my invention is the provision of a simple and efficient machine to cut a notch of measured depth in a key bit.

Another object of my invention is the provision of an efficient machine by which keys may be both originated and duplicated. 65

A still further object of my invention is the provision of a device by which a key bit may be cut to measurement so as to produce 70 an original key or to reproduce a key as originally cut.

Still another object of the invention is to produce a machine, by which key bits of different cuttings may be made by means of a 75 simple adjustment of stops or the like and without the taking off and replacement of various parts of the machine.

Further objects of the invention are to provide for relative movements of the cutter 80 and the key, both longitudinally and transversely of the key axis; to provide improved means for regulating and indicating the depth of the notch cut in the key; to provide improved means for spacing the 85 notches longitudinally of the key bit; to provide improved means for presenting the key to the cutter; and generally to construct a device of the character described which will possess simplicity of construction, efficiency 90 in operation and which may be operated by those not especially skilled in this line of work. 95

To these and other ends the invention consists in the novel features and combinations 100 of parts to be hereinafter described and claimed.

In the accompanying drawings:

Fig. 1 is a side elevational view of a key cutting machine embodying my improvements; 105

Fig. 2 is a top plan view of the same;

Fig. 3 is a rear end view of the device;

Fig. 4 is a sectional view on line 4-4 of Fig. 1; 110

Fig. 5 is a sectional view of the movable carriage taken upon on line 5-5 of Fig. 1;

Fig. 6 is a transverse sectional view taken on line 6-6 of Fig. 1 looking in the direction of the arrows; 115

Fig. 7 is a longitudinal sectional view taken upon line 7—7 of Fig. 2;

Fig. 8 is a detail sectional view of the spacing bar and key clamp taken upon line 8—8 of Fig. 2;

Fig. 9 is a sectional view similar to Fig. 7, but showing the carriage in its forward position; and

Fig. 10 is a detail view of two keys, one shown prior to the operation of cutting and one shown after the notches have been cut in the bit thereof.

The key cutting machine which I have chosen to show my improvements in their preferred form consists of a supporting frame, which I designate by the letter A, a cutting mechanism B, a carriage frame C, a key clamp D, and an indicating gauge mechanism E. To bring the key, when secured in the key clamp into contact with the cutter, it is, of course, essential to move either the key or the cutter relatively to each other. To accomplish this I have shown the carriage frame C, which carries the key clamp D as movably mounted upon the frame A, so that the key which is supported in the clamp upon the carriage may be moved into position to be engaged and operated upon by the cutter. But, while it is necessary to produce a relative movement of the cutter and key, it is not to be understood that my improvements are to be limited to that type of machine wherein the key is moved into engagement with the cutter, as such an arrangement is merely shown by way of illustrating a preferred form of my device.

To proceed with the detailed description of the different parts of the device, the supporting frame consists of a base plate 10, provided with a plurality of upstanding arms or standards which are adapted to support the different elements of the machine. The base plate comprises a forward relatively narrow portion 10^a upon which the two arms 11 supporting the cutting mechanism are carried, and a broader rear portion 10^b from which rise four relatively shorter arms 12 provided at the corners respectively of the rear portion of the base plate. A pair of arms 13 and 14, which are situated in alignment with each other near the longitudinal center of the base plate to support the gauge mechanism E, are carried by the rear portion 10^b of the plate. The supporting arms 11 may be, if desired, made separately from the base plate and detachably secured thereon, so if it is desired to secure wheels of varied dimensions upon the plate, arms of varied length may be attached to the plate to properly support the cutters in relation to the other mechanism.

These two arms are provided near their upper ends with journals 15, in which is loosely mounted a shaft 16 upon which a rotary cutting wheel 17 is secured in any

suitable way. As shown, a spacing collar 18 is secured upon the shaft and the cutter is locked against this collar by means of a nut 19, which is threaded upon the shaft 16. The cutter 17 is thus securely held against movement longitudinally of the shaft. The cutter shaft 16 may be rotated by any suitable means, but I have shown for this purpose a gear 20 adapted to be rotated by a crank 21, which gear is shown as in mesh with a pinion 22 secured rigidly upon the shaft 16. The gear 20 is provided with a suitable stub shaft 23 which is rotatably supported in a journal 24 provided upon the forward end of the base plate 10^a. A set screw 25 may be set into the journal 24 to retain the shaft of the gear 20 within this journal.

The arms 12 are provided in pairs with aligned openings 26 which serve to support guide rods 27 upon which the carriage C is movably mounted. These rods are secured within the openings 26 by set screws 28 shown more particularly in Fig. 2. The carriage C consists of a supporting plate 29 from which depend four perforated lugs 30 by which the carriage is slidably mounted upon the rods 27. As shown, the pairs of lugs upon each side of the machine receive one of the rods 27 within the perforations thereof, and thus a satisfactory and reliable mounting is provided for the carriage. The plate 29 is provided at its under side with a depending stop lug 31, the purpose of which will be hereinafter described and is also provided upon its underside with a lug 32 which has a cam face 33 at one corner thereof to cooperate with the cam shaped end 34 of a lever 36, which is pivoted at 37 to the upper end of the arm 14, as shown more particularly in Fig. 7. The cam portion of the lever is provided with a stop pin 38, which serves to contact with the standard 14 to limit the movement of the lever in a clockwise direction past the position shown in full lines in Fig. 5. A spiral spring 39 is coiled about each of the guide rods 27 and is compressed between the rear perforated lug 30 and a pin 40 which passes through the rod 27 adjacent the forward lug 30. As may be clearly seen from Figs. 2 and 5, when the cam lever 36 is turned from the full line position shown in Fig. 5, the cam 34 of this lever will by its contact with the cam surface 33 of the lug 32 move the carriage C toward the right in this figure, so that the key clamp will be moved toward the rotary cutter. The movement of the carriage forwardly toward the cutter will compress the springs 39 between the lugs 30 and the pins 40, so that when pressure is released upon the lever 36, the carriage will be moved back to its normal position by the springs. The contact of the cam surface 33 with the lever 34 will at this time move the lever back to normal position, the stop 38 contacting with the standard 14 just

prior to the contact of the rear lugs 30 with the supporting arms 12. The arrangement of the stop 38, just described, while, of course, not essential to the operation of the machine, will prevent any loose play of the parts and any lost motion of the lever 36. As shown in Fig. 5, the stop lug 31 is provided upon the lower face of the lug 32, but such an arrangement is not essential, as these lugs may be formed entirely separately.

The carriage C is provided at the rear of the plate 29 with a supporting rod 41, which serves to mount the key clamp D, as will be more fully described hereinafter. The carriage is provided at its forward portion in front of the plate 29 with two threaded perforated lugs 42 which support the key spacer bar 43. Threaded set screws 44 are inserted through the perforated lugs 42 and are adapted to rotatably support upon their opposing ends the spacer bar which is provided with a knurled wheel 45 by means of which the same may be turned to different positions. The spacer bar 43 is provided with a plurality of rows of openings 46, as shown in Figs. 2 and 5. Three of such rows of openings are shown in the drawings, but it is, of course, obvious that the bar may be provided with any number of such openings which is desired, and that the spacing of the different openings within the rows may be varied, as desired. It will be seen that as the spacing of the openings in the different rows 46 will determine the distance between the notches which are cut in the key, that it will be desirable to have the openings of each row spaced the same distance apart. One row, however, may begin at any desired place upon the bar 43 and may have any desired spacing with relation to that of the openings of the remaining rows. To provide for the stopping and the yieldable retention of any one of the rows 46 in position with relation to the carriage C, a plurality of recesses or depressions 47 are provided upon the side face of the knurled wheel 45 and are adapted to receive a pin 49 spring-pressed by a coil spring 50, which pin and spring are set in a socket 51 formed in the plate 29 and retained therein by the small set screw 52. There are preferably as many of the recesses 47 as there are of the rows of openings 46, and one of the recesses will come into registration with the spring-pressed pin 49 when one of the rows of openings 46 is positioned upon the top of the spacer bar to properly cooperate with the key clamp D.

The key holder or clamp D consists of a lower plate 55, which is provided with a depending lug 56, having a transverse opening 57 by which it may be slidably and rotatably mounted upon the supporting rod 41 upon the carriage C. The plate 55 is also provided with an upstanding lug 58 transversely perforated to receive a rod 59, which

is secured against movement therein by a set screw 60, which will be best shown in Figs. 4 and 7. Upon the rod 59 upon opposite sides of the lug 58 are mounted the forked arms 61 and 62 of a clamping plate 63, which cooperates with the plate 55. The clamping plate 63 is rotatably mounted upon the rod 59, so that it may swing about this rod relatively to the plate 55 to spread the clamp so that a key may be inserted therein. A plate 64 of hard steel is provided near the front end of the plate 55 and a similar plate 65 is provided near the forward edge of the plate 63. These plates 64 and 65 are adapted to serve as the clamping surfaces of the key clamp and are made of some wear resisting metal. The plate 64 is provided with the shoulder 66 against which the rear edge of the key bit is adapted to rest. The two plates 55 and 63 may be forced into clamping relation by means of a screw 67 which is secured in the lower clamping plate 55, passes through a perforation 68 provided in the plate 63, and is designed to receive a wing nut 69 upon its threaded upper end, which by contact with the plate 63 will force this plate toward the plate 55 in a well known manner. To spread the clamping members when the wing nut 69 is backed off from the screw 67, there is provided in the lower plate 55 a small rubber pin or button 70, which projects from without the plate 55 and contacts with the lower surface of the plate 63 to resiliently force the latter plate upwardly, so that the key may be released from the clamp when the wing nut is turned in the proper direction. A key 71 is shown in dotted lines secured within the clamping plate 64 and 65 in Figs. 1, 7 and 8 of the drawings.

The forward portion of the lower clamping plate is at the under side rounded out transversely, as shown at 72 in Figs. 7 and 8, to correspond to the shape of the spacer bar 43, so that the portion of the bar which lies above the plate 29 will snugly fit within the portion 72 of the plate 55. As shown in Fig. 7, this arrangement will permit the lower plate of the key clamp to lie substantially parallel with and closely adjacent to the upper surface of the plate 29. A pin 73 is provided within the rounded portion 72 of the key clamping plate 55 and extends downwardly to engage in one of the openings in the spacer bar 43, so that the key clamp will be secured thereby against accidental transverse movement. When one notch has been cut in the key and it is desired to move the key transversely of the cutter to cut the adjacent notch, the clamp is raised until the pin 73 clears the spacer bar and then is moved transversely until the pin will drop into the next opening of the bar. This is repeated each time a new

notch is cut in the key. The clamp is provided with a positioning member 75, which consists of a U-shaped member having a bight portion constituting a forwardly disposed beveled head 76, and two spaced arms 77. These arms are rotatably mounted upon the pin 59, so that they will always be moved with the clamp, but may be swung about the pin 59 relatively to the clamp D. The positioning member is yieldingly maintained in the position relatively to the clamp shown in Figs. 1 and 3, and in dotted lines in Fig. 7 by two springs 78 and 79, which are, as shown in Fig. 4, coiled about the rod 59 and whose ends are secured to the arms 77 of the positioning member 75. These springs provide means to maintain the positioning member out of the way of the cutter when once the key has been positioned and clamped within the clamping member D. The indicating gauge mechanism E consists of a shaft 80 which is rotatably supported by the standards 13 and 14, previously described, as best shown in Fig. 7. This shaft is threaded, as shown at 81, and is adapted to slidably receive a disk member 82 provided with a hub 83, which is keyed thereon to rotate with the shaft by key member 82a. The disk 82 is adapted to be secured in position longitudinally of the shaft 80 by a plurality of lock nuts 84, which are threadedly received upon the shaft upon each side of the disk 82 and hub 83, so that the disk may not only be secured in position, but may be adjusted relatively to the shaft. The shaft extends from the rear portion of the frame without the standard 14 and upon this extended end is secured a knob 85, which may be grasped by the fingers of the operator to turn the shaft. The disk 82 is provided upon its rear face or the face which is opposed to the knob 85 with a plurality of pins 86 provided with enlarged heads 87. The heads 87, as clearly shown in Figs. 4 and 7, are of different height, so that they project at different distances from the surface of the disk 82. As best shown in Fig. 7, these pins cooperate with the stop lug 31 upon the carriage C, so as to limit the movement of this carriage toward the cutter. As will be clearly understood, when the shaft is turned by the knob 85, the pins upon the disk 82 are moved so that different pins may be selectively placed in the path of the stop lug 31, so as to vary the position in which the carriage is stopped to cut notches of different depth in the bit of the key.

A plate 89 is attached to the supporting arm 14 and extends within a recess 90 formed upon the shaft 80 between the arm 14 and the knob 85 to secure this shaft against longitudinal movement in its bearings while still permitting the rotation of the shaft. The knob 85 upon its inner face is provided with a plurality of recesses 91,

which are adapted to cooperate with a spring-pressed pin 92 seated in a socket 93 in the supporting arm 14. The engagement of the pin within these recesses 91 will yieldingly retain this knob and the shaft 70 to which it is secured in any adjusted position, so that the desired stop pin 87 may be yieldingly retained in the path of the stop lug 31. The knob upon its outer face is provided with a plurality of numerals 94 75 which serve to indicate the length of the pins 87 and will, therefore, serve to indicate the depth of the notch which the particular pin opposite that numeral will permit to be cut in the key bit. The longest pin head 87 is opposite the numeral 1 and the pin heads gradually decrease in length from 1 to 0, so that the shortest one is opposite the numeral 0. It is seen, therefore, that when the numeral 1, for instance, is uppermost, the longest pin will be in the path of the stop 31, so that the shallowest notch would be cut in the key bit at that time and the deepest notch would be cut when the numeral 0 was positioned uppermost upon the knob 85.

The operation of my device is as follows: In Fig. 10 I have shown at 95 a key blank which is adapted to be placed in my improved key cutting machine, so that notches may be cut in the bit thereof to provide the finished key, as shown at 95a in that figure. The clamping jaws of the key clamp D are loosened up by the backing off of the wing nut 69 and a key is placed between the two steel clamping plates 64 and 65 with its rear edge against the shoulder 66. The positioning member 75 is then swung about its pivot until it is in the position relative to the key clamp shown in full lines in Figs. 7 and 8. The rear bevel face of the head 76 of this member will contact with the front straight bit of the key, so that the key will be forced back in the clamp tightly against the shoulder 66, while the edge 96 of this member will contact with the shoulder 97 upon the key to properly position the key longitudinally of its axis. The wing nut is then turned down so that the key will be clamped tightly between the clamping plates. The key clamp which may be in the position shown in Fig. 7, or in the position shown in Fig. 8 when the key is inserted therein, according to the wishes of the operator is now moved transversely of the carriage until the pin 73 drops into the proper opening 46 to cut the first notch at the desired position upon the key bit. It will be understood that the spacer bar has first been turned so that the proper row of openings 46 will be presented upwardly to cooperate with the pin 73, so that the proper spacing of the notches upon the key bit will be effected. The knob 85 is then turned until the selected pin 87 is positioned in

the path of the lug 31, so that the notch of the desired depth will be cut in the key bit when the carriage is advanced. With the pin securely positioned in the proper 5 one of the openings 46, the lever 36 is moved from the full line position in Fig. 5 to the dotted line position shown in this figure by one hand of the operator, while the crank 21 is turned with his other hand provided 10 that power means is not supplied for operating the cutter. The rotary cutter will then be turned and the key will be advanced toward the cutter to engage the same so that by continued pressure upon the lever 36 the 15 cutter will operate upon the key until the advance of the carriage toward the cutter will be stopped by contact of the stop 31 with the selected pin 87.

When the carriage has been stopped by 20 the pin 87 and the first notch has been completed, the key is then moved transversely of the carriage but longitudinally of its own axis by swinging the clamp upwardly about the rod 57 until the pin 73 has been disengaged from one of the spacing openings 46 and then sliding the key clamp along this rod until the pin 73 drops in the adjacent opening which positions the key bit for the cutting of the second notch. The knob 85 is then turned until the numeral which is brought uppermost will signify that a notch of the desired depth will be cut and the lever and crank are operated as before and the operation is continued until the completed key is turned out.

When one key is completed, it is removed from the clamp and a second one is inserted and cut in the same manner. It will be seen that each key, and in fact each notch of the 40 key is cut singly and is cut at any desired point upon the bit of the key and is made of any desired depth, so that a key bit of any desired configuration may be made regardless of whether a duplicate of the same 45 is at hand or not.

As the rotary cutters used by different lock manufacturers are not always of the same width and the bevel of the cutting edges is not always the same, it will be 50 found desirable to so mount the rotary cutter 17 that it may be easily removed and another substituted in its place. In the form of my invention shown in the drawings, I have provided for such a substitution by detachably securing one of the standards 11 to the bed plate 10^a of the device by means of the screw 11^a. It will be obvious that by the removal of this screw, the standard 11 may be removed from the bed plate and from 60 the end of the shaft 16, so that by the removal of the nut 19 the rotary cutter may be slipped off the shaft and a new one substituted in its place and the parts replaced as before. It will be seen that this will 65 provide a convenient and satisfactory ar-

rangement for removal of the rotary cutter and the substitution of another therefor.

In somewhat the same manner I have provided means by which the stop disk 82 may be removed from its shaft and another stop disk containing pins of other dimensions may be substituted therefor. The standard 14 is detachably mounted upon the plate 10^b and is secured to the plate by the screw 14^a. It will be obvious that by the removal of this 70 screw the standard, the shaft 80, which is mounted therein, and the mechanism which is secured on this shaft may all be easily removed from the frame. By the removal of the two lock nuts 84 which are positioned 75 between the disk 82 and the front end of the shaft 80, the disk may be removed from the shaft and another one to be in its place. The nuts may then be replaced upon the shaft and the shaft and standard replaced in position 80 and when the screw 14^a is again tightened in place, the device will be ready for use. By this arrangement I am able to arrange for any desired cutting of a key blank by merely providing interchangeable 85 disks upon which will be mounted pins 87 of suitable dimensions.

While the broad principles of my invention have been exemplified by a device in which the axis of the rotary cutter is fixed and the key is movable both transversely and longitudinally of its own axis, so that it may be properly presented to the cutter, it will be understood that the invention is not limited to this exact arrangement, which is merely illustrated as a preferred embodiment 90 of the novel principles involved. Moreover, while I have shown and described a preferred form of my invention, it will be understood that the broad principles thereof may be 95 embodied in many modifications and variations which will fall within the spirit of the invention and within the scope of the appended claims.

What I claim is:

1. A key cutting machine, comprising a cutter and a carriage slidably movable relatively thereto, a plurality of stops selectively movable into position to contact with the carriage to variably limit such movement, and a key holder mounted on the carriage.

2. A key originating machine comprising a cutter and carriage movable relatively to each other, means selectively movable into a plurality of predetermined positions to limit such movement and a key holder mounted on said carriage in position to present a key to the cutter.

3. A key originating machine comprising a cutter and carriage movable relatively to each other, a plurality of stops selectively movable into position to varyingly limit said movement and a key holder mounted on said carriage in position to present a key to the cutter.

4. A key cutting machine comprising a relatively movable key carriage and cutter, means adjustable to variably limit the relative approaching movement of said members to cut notches of measured depth in the key bit, and a key holding device mounted on the carriage for movement transversely thereof, and cooperating means on said device and carriage to retain the former in adjusted transverse positions.
5. A key originating machine comprising a cutter, a key holding carriage movable relatively thereto, a plurality of stops selectively movable in position to limit the movement of the carriage and a key holder mounted on said carriage in position to present a key to the cutter.
6. A key originating machine comprising a cutter, a carriage movable relatively thereto, a plurality of stops selectively movable into position to contact with a portion of the carriage at different positions in its movement and a key holder movably mounted on the carriage.
7. A key originating machine comprising a cutter, a key supporting carriage movable relatively thereto, a plurality of stops of different dimensions selectively movable in position to limit the movement of the carriage and a key holder movably mounted on the carriage.
8. In a key originating machine, a cutter, a key holding carriage reciprocably mounted in cooperative relation thereto, means for limiting the movement of the carriage toward the cutter including a pin in the path of a portion of the carriage and movable to inoperative position in a plane at right angles to the direction of movement of the carriage.
9. A key originating machine comprising a cutter, a carriage movable relatively thereto, a plurality of stops selectively movable into position to contact with a portion of the carriage at different positions in its movement, and extending longitudinally thereof and a key holder mounted on said carriage in position to present a key to the cutter.
10. In a key originating machine, a cutter, a key holding carriage reciprocably mounted in cooperative relation thereto, means for limiting the movement of the carriage toward the cutter, including a plurality of stops of different lengths selectively movable to extend longitudinally in the path of movement of a portion of the carriage and a key holder movably mounted on the carriage.
11. In a key originating machine, a cutter, a key carrier movably mounted relative thereto, means for limiting the movement of the latter toward the former including a rotatable member carrying a plurality of stops selectively movable in the path of the key carrier and a key clamping device mounted on said carrier.
12. In a key originating machine, a cutter, a key carrier movably mounted relative thereto, means for limiting the movement of the latter toward the former including a rotatable disk carrying a plurality of pins of different lengths selectively movable into the path of a portion of the carrier and a key clamping device mounted on the carrier for movement across the face of the cutter.
13. In a key originating machine, a cutter, a carriage reciprocably mounted to move toward and from the cutter to present the key bit thereto, and withdraw it therefrom, and resilient means to urge the carrier away from the cutter.
14. In a key originating machine, a cutter, a reciprocably mounted carriage, said carriage being movable toward the cutter to cause the latter to operate on the key, and resilient means to withdraw the carriage from the cutter at the close of said operation.
15. A key originating machine comprising a cutter, a carriage disposed in operative relation and movable with respect thereto, a series of stops arranged to selectively contact with the carriage to permit a measured relative sliding movement between the cutter and carriage means to indicate the movement permitted and a keyholder mounted on said carriage.
16. A key originating machine comprising a cutter, a carriage slidably movable relatively thereto, means to variably limit the movement of the carriage, an indicator to show the movement permitted said carriage, and a key holder mounted on said carriage for movement transversely thereof to present different portions of the key bit to the cutter.
17. A key originating machine comprising a cutter and a carriage movable relative to each other, a plurality of stops selectively movable into position to varyingly limit said movement, means to indicate the stop selected and a key holder mounted on said carriage.
18. In a key cutting machine, a movable carriage provided with a key holding clamp mounted thereon for movement transversely thereof, and means to space and retain said clamp in various transverse positions on the carriage.
19. A key cutting machine comprising a cutter, a carriage movable toward the cutter, a key holder adjustable on the carriage transversely of the cutter, and means to retain the key holder in adjusted position said holder being movable out of engagement with said retaining means for adjustment to another position.
20. A key cutting machine comprising a cutter, a carriage movable relatively thereto, a spacer bar on the carriage and a key holding clamp adjustable on the carriage along

said spacer bar and movable into and out of engagement therewith.

21. A key cutting machine comprising a cutter, a carriage movable toward and from the cutter, a key holding device mounted on the carriage and movable transversely of the cutter, and spacing means to adjust the transverse movements of the key holder, said key holding device being movable into and out of engagement with said spacing means.

22. A key cutting device comprising a frame, a spacer bar carried thereby, means adjustable along said spacer bar transversely of the carriage, a key clamp carried by said means and co-operating means carried by said spacer bar and adjustable means to retain the latter in adjusted position.

23. In a key cutting device, a cutter, a key carrier slideable toward and transversely of the cutter, a spacer bar to regulate said transverse movements and a key holder mounted on said carriage in position to present a key to the cutter.

24. A key cutting machine, provided with a movably mounted key holding clamp, said clamp being mounted for movement transversely and longitudinally of the machine to present the key bit to the cutter, and means to space and retain said clamp in various transverse positions to determine the position of the notches cut in the key bit.

25. In a key cutting machine, a frame, a cutter, a carriage movable toward and from the cutter, a key clamp supported thereon and adjustable transversely thereof, and means to set and retain said clamp in predetermined spaced positions of adjustment.

26. In a key cutting machine, a frame, a cutter, a key holder adjustable transversely thereof and a spacer bar on the frame to retain said holder in adjusted position, said holder being pivotally mounted to be swung out of engagement with said spacer bar.

27. In a key cutting machine, a frame, a spacer bar mounted thereon, a key clamp adjustable longitudinally of the spacer bar and cooperating means on said clamp and bar to space said clamp in various positions transversely of the frame.

28. In a key cutting machine, a frame, a key clamp adjustable transversely thereof, and a spacer bar mounted on the frame below said clamp, cooperating with said clamp, and provided with spaced means to retain said clamp in adjusted positions.

29. In a key cutting machine, a frame, a key clamp adjustable transversely thereof, a spacer bar cooperating with said clamp and provided with a plurality of sets of spaced means to retain said clamp in adjusted position, said sets being arranged to vary the adjustment of said clamp.

30. In a key cutting machine, a frame, a key clamp adjustable transversely thereof, a

spacer bar cooperating with said clamp and provided with a plurality of sets of spaced means to retain said clamp in adjusted position, the means of one set being spaced differently from the means of another set, 70 said bar being movable to bring a selected set into operative position.

31. In a device of the class described, a rotatable cutter and a key holder relatively movable with respect to each other to present different portions of the bit of the key to said cutter, means to retain the key holder in adjusted position while a notch is being cut in the key, said holder being swingable about an axis parallel to the axis of the cutters out of engagement with said means.

32. In a device of the character described, a cutter and a key holder relatively movable with respect to each other to present different portions of the bit of the key to said cutter and a spacer bar cooperating with said holder to space and retain it in adjusted position, said key holder being swingable about an axis transverse to the cutter out of engagement with said spacer bar.

33. A key cutting device comprising a cutter, a key carrier slideable toward and transversely of the cutter, a spacer bar to regulate and retain the carrier in adjusted transverse positions and means to limit the movement of the carrier toward the cutter.

34. In a key cutting device, a cutter, a key holder, movable relatively thereto, and means to retain said key holder in equally spaced positions relatively to said cutter to present equally spaced points on the bit of a key to said cutter, said means being arranged to vary the spacing of said points of the key bit presented to the cutter.

35. In a key cutting machine, a cutter, a key holder adapted to be advanced across the cutting edge thereof to present different portions of the bit of the key to said cutter, and means providing for the advance of the key holder in equal steps, said key holder being swingably movable out of engagement with said means about an axis transverse to the cutter.

36. In a key cutting machine, a cutter, a key holder adapted to be advanced across the cutting edge thereof to present different portions of the bit of the key to said cutter, and means providing for the advance of the key holder in equal steps, said means being adjustable to vary the length of said steps.

37. A key originating machine comprising a cutter, a key holder movable transversely and longitudinally relatively thereto to present different portions of the key bit to the cutter and means engaging said holder for varyingly spacing said transverse movement to vary the distance between the notches cut in the key bit.

38. In a key cutting machine, a cutter, a carriage movable toward and from the cut-

5. ter, and a key holder movable on the carriage transversely of the cutter, means to limit the movement of the carriage to a predetermined extent, and means to set the key holder in predetermined positions upon the carriage.

10. 39. In a key cutting machine, an adjustable key holder, a spacer bar cooperative therewith and provided with a plurality of sets of spaced retaining members, the members of one set being differently spaced from those of another set.

15. 40. In a key cutting machine a key holder, a spacer bar cooperating therewith and provided with a plurality of sets of spaced retaining members, the members of one set being differently spaced from those of another set, and means for yieldingly retaining said spacer bar in position to render operative a 20 selected set of retaining members.

25. 41. In a key cutting machine a key holder, a spacer bar cooperating therewith and provided with a plurality of sets of spaced retaining members, the members of one set being differently spaced from those of another set, said bar being rotatable to place a selected set of retaining members in operative position.

30. 42. In a key cutting machine, a movable carriage, a key holder movable thereon, and provided with a stop pin, a spacer bar mounted upon the carriage and provided with spaced openings to receive said pin.

35. 43. In a key cutting machine, a movable carriage, a rod carried thereby a spacer bar, and a key holding clamp swingably mounted on said rod to be moved in and out of engagement with the spacer bar.

40. 44. In a key cutting machine, a key carriage, a rod carried thereby and a key holding clamp mounted to slide longitudinally of said rod, a spacer bar with which said clamp is adapted to engage and said clamp being rotatable about said rod into and out 45 of engagement with said spacer bar.

45. 45. In a device of the class described, a key holding clamp and a U-shaped positioning member adapted to be swung over the mouth of the clamp to position a key therein, so that the bight portion of said member engages the bit of the key in said clamp.

50. 46. In a device of the class described, a key holding clamp and a positioning member adapted to be swung over the mouth of the clamp to contact with the key bit substantially along the entire edge thereof, and position a key therein.

55. 47. In a device of the class described, a key carriage, a key holding clamp movably mounted thereon, and a positioning member movably mounted to swing to a position over the mouth of the clamp, and contact with the key along the entire bit thereof.

60. 48. In a key cutting machine, a cutter, a

key holding clamp mounted in position to 65 present a key to a cutter, a key positioning member swingable over the edge of the key bit and between the bit and the cutter and contact with the key along the entire bit thereof to position the key in the clamp. 70

49. A key holding clamp and a key positioning member cooperating therewith, said member having an edge to cooperate with a shoulder on the key and a beveled face to cooperate with the key bit. 75

50. A key holding clamp having a pivotally mounted jaw, and a movable key positioning member pivoted coincidently with said jaw.

55. 51. A key holding clamp and a key positioning member movably mounted relatively thereto, said member being movable to position a key in the clamp and means for normally holding said member in inoperative position. 80

52. A key holding clamp and a key positioning member movably mounted relatively thereto, said member being movable to position a key in the clamp and a spring for normally holding said member in inoperative 90 position.

57. 53. In a key cutting machine, a frame, a cutter, a carriage mounted thereon for horizontal movement, said carriage being yieldingly urged in one direction, a cam for moving said carriage in the opposite direction and means to limit the movement of the carriage toward the cutter. 95

62. 54. In a device of the class described a frame, a cutter, a carriage mounted thereon for horizontal movement, a lever to move said carriage in one direction, a spring for moving said carriage in the opposite direction and means to variably limit the movement of the carriage toward the cutter. 100

67. 55. In a key cutting machine, a frame, a cutter mounted on the frame, a carriage movable toward and away from the cutter, a key holder mounted on the carriage and movable transversely thereof, and a plurality 110 of stops movable across the path of the carriage to bring a selected stop into position to limit the movement of the carriage toward the cutter.

72. 56. In a key cutting machine, a cutter, a carriage movable relatively thereto, a key holder movably mounted relatively to the carriage and spacing means to retain said key holder in adjusted positions. 115

77. 57. A key cutting device, comprising a cutter, a key carrier slidable toward and transversely of the cutter, a spacer bar to retain the carrier in adjusted transverse position, and means to limit the movement of the carrier toward the cutter, comprising a rotatably mounted disk having on one face thereof a plurality of stop members. 120

82. 58. A key cutting device, comprising a

cutter, a key carrier slidable toward and transversely of the cutter, a spacer bar to retain the carrier in adjusted transverse position, and means to limit the movement of the carrier toward the cutter, comprising a rotatably mounted disk having on one face thereof a plurality of stop members, and means to rotate said disk to bring said members selectively into operative position.

59. A key cutting device, comprising a cutter, a key carrier slidable toward and transversely of the cutter, a spacer bar to retain the carrier in adjusted transverse position, and means to limit the movement of the carrier toward the cutter, comprising a rotatably mounted disk having on one face thereof a plurality of stop members, means to rotate said disk to bring said members selectively into operative position, and means 20 to indicate the selected member.

60. A key cutting device, comprising a cutter, a key carrier slidable toward and transversely of the cutter, a spacer bar to retain the carrier in adjusted transverse position, and means to limit the movement of the carrier toward the cutter, comprising a rotatably mounted disk having on one face thereof a plurality of stop members, and

a stop member indicator mounted to rotate with said disk. 30

61. In a machine of the character described, the combination of a rotatable cutter, a carriage movable toward the cutter, a spacer bar, and a key holder swingably mounted on the carriage to move into and 35 out of engagement with the spacer bar.

62. In a key cutting machine, a cutter and a key holder movable relatively to each other, stop means rotatably adjustable to positions to variably limit said movement 40 and means to yieldingly retain said stop means in adjusted position.

63. A key originating machine having a frame, a carriage movably mounted thereon provided with a key holding clamp, said 45 clamp being transversely movable relatively to the carriage to present different portions of the key bit to the cutter, and cooperating adjustable means on the frame and carriage to variably limit the movement of the carriage toward the cutter to cut a notch of the desired depth at any point along the bit of the key. 50

In witness whereof, I have hereunto set my hand this 21st day of March A. D., 1921.

JOHN H. SHAW.
